HANDLE END HOLDER AND INSTALLATION

Daniel I. Reiter, New York, N. Y.

Application May 6, 1952, Serial No. 286,264

5. Claims. (Cl. 150—12)

1

This invention relates to holders for the ends of pocket book handles and particularly to handle holders for box-like pocket books or those having relatively rigid sides.

The invention contemplates the provision of a handle holder adapted to be completely concealed, together with the handle end to which it is attached, within an aperture in the side wall of the pocket book, a head or extension on the holder lying flat against the inner face of said side wall above and below the aperture, so that a flat face is provided on the inside surface of the pocket book side, free of objectionable protuberances or projecting parts.

The invention further contemplates the provision of a holder having arms so shaped that they are predisposed to bend and are therefore easily bent into firm clamping relation to the end of a pocket book handle, and easily secured to the wall of a pocket book substantially flush therewith and without protruding therefrom merely by passing the handle through an opening in said wall without the need for rivets, tacks or other wall-penetrating fasteners.

The invention further contemplates the provision of a simple and efficient handle holder adapted to be made economically of sheet metal, having bendable handle clamping arms adapted to be concealed within an aperture in the side wall of a box pocket book and joined by an integral head adapted to lie flat against the side wall to prevent the handle from pulling out, the head being later covered by the usual pocket book lining and preventing the holder from being materially dislocated relatively to the aperture, one or more prongs being optionally provided to enter the side wall for preventing rotation of the holder and handle end in the aperture, should the arms not fit well in said aperture.

The invention further contemplates the provision of a pocket book handle installation for a box-like pocket book avoiding all necessity for projecting parts extending beyond the facing of the pocket book or projecting inwardly of the inner surface of the side wall to secure the handle in place but on the contrary being free of protuberances or projections and making possible a substantially flat inner surface on the pocket as well as a flat facing surface on outside, the fastening means for the handle being quickly and easily arranged and permanently secured in an aperture in said wall, the end of the handle extending through a slot in the outer facing and into the aperture.

The various objects of the invention will be

2

clear from the description which follows and from the drawings, in which:

Fig. 1 is a perspective view of the handle holder, showing in dash-dot lines positions assumed by the clamping arms when secured to a handle end.

Fig. 2 is a similar view of a modified form of the holder, wherein the wall-engaging head is extended transversely and the prongs are located differently from those shown in Fig. 1.

Fig. 3 is an elevational view of another modified form of the holder, wherein the transverse extensions of the lower part of the holder shown in Fig. 2 are omitted, and the prongs are differently arranged.

Fig. 4 is a fragmentary elevational view of a handle installation for a pocket book having relatively rigid side walls of considerable thickness, the outer covering or facing being partly broken away to show the interior structure.

Fig. 5 is a vertical sectional view of the installation taken on the line 5—5 of Fig. 4, the thicknesses of the parts being exaggerated for clarity.

Fig. 6 is a horizontal sectional view of the installation taken on the line 6—6 of Fig. 4.

Fig. 7 is a vertical sectional view similar to Fig. 5, of a modified form of the installation wherein the wall of the pocket book is laminated of several layers of material and the aperture for the holder is made through the inner layers only.

In the practical embodiment of the invention shown by way of example, and referring first to the pocket book handle installation illustrated in Figs. 4—6, the handle 10 is shown as of substantially rectangular cross section and attached to the side wall 11 of a pocket book by my improved holder or anchor which is designated generally by the numeral 12. The handle end 13 is passed through a suitable slot 14 in the outer covering or facing sheet 15 of the side wall, and through the aperture 16 in said wall before the lining 17 is secured to the inner surface of the substantially rigid side wall 11. After the handle end 13 is passed through said aperture to the inside of the wall, it is arranged in the space between the two laterally extending arms 18 and 19 of the holder 12 and against the inner flat portion 20 constituting an integral connector portion for, and arranged in a plane at substantially right angles to, said arms 18 and 19.

Together with the connector, the upper portion 21 extending upwardly from the connector and the lower portion 22 extending downwardly from the connector, form the enlarged head of

the holder or anchor, said head being preferably flat whereby the connector portion 20 and the portions 21 and 22 are coplanar. After receiving the handle end between them, the arms are bent into the handle-clamping positions thereof shown in Figs. 4 and 6, around and into tightly pressed engagement with a portion of the handle end 13, thereby to secure the holder adequately to said end portion without the need for rivets or other penetrating fasteners. After the handle and the holder are fastened together, the handle is pulled in a direction to draw it out of the slot 14 as far as it will go, to arrange the bent arms 18 and 19 and the handle end 13 inside of the aperture 16. In this position, the connector portion 20 of the head bridges the inner end of the aperture and closes said end, the upper extension 21 of the head engages that part of the inner surface 23 of the side wall which is above the aperture, and the lower extension 22 engages the inner surface of the side wall below the aperture, the head thereby preventing the handle end from being pulled out of the wall through the slot 14. The holder or anchor 12 being of relatively thin sheet metal, it is obvious that the head thereof does not project inwardly of the wall surface 11 to any material extent. Consequently, when the lining 17 is secured in place to said surface thereby to finish the inside of the pocket book, the lining covers and conceals the entire head. There is thus provided a substantially smooth inside surface on the pocket book side, free of projections such as would result if the aperture 16 were omitted, and if the bent arms 18 and 19 instead were in direct contact with the inner surface 23 of the side wall.

Obviously, a pull on the pocket book handle, or the tension to which such handles are normally subjected, maintains the head of the holder or anchor in pressed contact with said inner surface 23. When the handle, which is usually flexible, is released from tension, it merely sags without any tendency to move inwardly through the slot 14 into which it is preferably frictionally fitted. The material of the facing sheet 15 just below the slot 14 covers the front end of the aperture 16 and conceals the arms 18 and 19, whereby nothing except the handle is visible at or protrudes from either face of the side wall to interfere with the free movement of the hand of the user or to strike or injure the hand or other objects when inserted into the inside of the pocket book.

In those cases where the side wall of the pocket book is laminated or made of several layers of sheet material such as cardboard for example, resulting in a wall substantially thicker than the holder and handle end assembly as shown in Fig. 7, the aperture 30 for the reception of the arms of the holder is made only part way through the wall and only through some of the layers or laminations, but not through the outermost layer 31, which layer consequently covers the outer end of the aperture. However, a slot 32 sufficient for the passage of the handle and preferably aligned with the slot 14 in the facing sheet 15, is made instead in the layer 31.

As will best be seen from Figs. 1 to 4, the holder or anchor may take a variety of forms. In the form shown in Fig. 4, a pair of prongs as 36, 36a is provided at opposite corners of the respective extensions 21 and 22. Said prongs are pressed into the adjacent material of the side wall surface as 23 with which the head of the holder or anchor is in contact after the handle

10 has been pulled tight. The prongs prevent any tendency on the part of the holder and of the handle end assembly to rotate should the assembly fail to fit well into the aperture 16. If the assembly does fit snugly, the friction between it and the walls of the aperture is sufficient and can be depended on to avoid dislocation of the parts. In that case, no need for the prongs arises and they may be dispensed with entirely. When used, the prongs may be located at any convenient point, preferably at some corner of the head, as shown in Figs. 1-3.

In that form of the holder or anchor shown in Fig. 1, the flat head 35 is of generally rectangular shape and similar to the head of the holder or anchor 12 of Fig. 4, there being extensions 21 and 22 above and below the portion 20 connecting the arms. One such extension would permit rotation of the holder under the pull of the handle in a direction such that the assembly with the handle end would work its way out of the aperture, whether the extension is above or below the aperture. The extensions both above and below the handle are therefore desirable and preferable. A prong as 36 is bent from the material at a corner of the extension 21 and a similar prong 36a is similarly bent from a corner of the extension 22. In order that the arms 18 and 19 may be easily bent into clamping position and that they hold securely without cutting the handle end, the free end portion 37 of each arm is bent along a line 38 across the entire width of the arm into a plane inclined toward the corresponding free end portion of the other arm. The end portion is thereby predisposed to bend into a position perpendicular to the surface of the handle end for maximum clamping efficiency. In addition, the end edge 39 of the end portion of the arm is made concave and the corners 40 and 41 of said edge are convexly rounded thereby providing rounded prongs at the corners of the arms. When the arms are bent into clamping position, the rounded ends of the prongs bite into the relatively soft flexible material of the handle end without cutting or penetrating through the handle but compressing the material thereof until the prongs sink all the way into the handle end and are covered thereby (Figs. 5, 6 and 7).

In the modified form of the holder or anchor shown in Fig. 2, substantially parallel coplanar transverse extensions or wings as 45 and 46 form part of the flat head. The connecting portion 20 between the arms 18 and 19 is extended upwardly and downwardly as at 47 and 48 in the same plane as the wings 45 and 46 for a distance substantially equal to the thickness of the handle 10 to enable the handle to bend at the place where it emerges from between the arms and to pass out of the aperture in the wall of the pocket book, and also to make the holder symmetrical so that it may be used with either wing uppermost. The wing 45 extends transversely beyond the adjacent part 47 and the wing 46 extends similarly beyond the part 48 to form an I-shaped head wherein the wings are in contact with a substantial area of the inner surface of the side wall and more greatly resist pulling out of the wall under the tension on the handle. The prongs 49 are provided on the lower corners of the wing 45 while similar prongs 50 are formed on the upper corners of the wing 46 though it will be understood that such prongs may be located wherever convenient, or omitted if desired.

In Fig. 3 a holder or anchor is shown similar to that of Fig. 2, but with the lower wing 46 omitted and the part 48 extended downwardly for a distance about the same as the width of the upper wing 45 which is retained. The lower cross bar of the I being omitted, this form of the holder head is substantially T-shaped and combines some of the advantages of the heads of the holders of Figs. 1 and 2. The prongs 51 are here shown located at the upper corners of the 10 wing 45.

It will now be seen that I have provided a simple and economical handle end holder and installation designed to be readily and quickly assembled by unskilled persons without the need for rivets or other additional fasteners, that the flat thin head permits the extending arms of the holder to be concealed in an aperture of the side wall of a box-like pocket book while the head remains substantially flush with the inner surface of the side wall without any undesirable projections forming obstructions to the smooth contour of the wall, that no fastening means is required on the outside of the wall, that the assembly is self-held frictionally in position assisted by suitable prongs if desired, and that the holder and installation adequately carry out the intended purposes of the invention.

While certain specific forms of the invention have herein been shown and described, various obvious changes may be made therein without departing from the spirit of the invention defined in the appended claims.

I claim:

1. A pocket book handle installation comprising a handle having a flexible end strap portion, a rigid wall constituting the side wall of a pocket book, said wall comprising a relatively rigid member having an aperture therethrough, an inner imperforate lining for the member and an outer covering sheet for the outer surface of the member, said covering sheet having a slot of less area than the aperture formed therein in registration with a portion of the aperture, and a one-piece anchor of thin sheet metal for the end portion of the handle, said end portion passing through the slot and into the aperture, said anchor comprising a flat head bridging the innermost part of the aperture, a pair of side arms one extending outwardly from a part of one side edge of the head intermediate the ends of the head and the other extending outwardly from a corresponding part of the opposite side edge of the head, each of the arms being bent about the end portion of the handle toward the other arm and projecting from the head a distance less than the thickness of the rigid member and arranged and fitted entirely within the aperture, the outer surface of the head being normally in contact with the inner surface of the rigid member, the lining covering the inner surface of the head to form a substantially smooth surface on the inner face of the wall.

2. The installation of claim 1, the end portion of the handle having a bend therein at an end edge of the arms, said bend being within the aperture and biasing said end portion through the slot, the handle portion having a second bend therein beyond the slot and at the outside of the wall arranging the adjacent part of the handle in substantially parallel relation to that part of the handle held by said arms.

3. A pocket book handle installation comprising a handle having a flexible end strap portion, a rigid wall constituting the side wall of a pocket book, said wall comprising a relatively rigid member having an aperture therethrough, an inner imperforate lining for the member and an outer covering sheet for the outer surface of the member, said covering sheet having an opening of less area than the aperture formed therein, said opening registering with a portion of the aperture, and a one-piece anchor of thin sheet metal for the end strap portion of the handle, said end strap portion passing through the opening and into the aperture, said anchor comprising a flat body bridging the aperture at the inner surface of the member, a pair of spaced apart confronting arms extending outwardly from the body and bent about the end strap portion of the handle toward each other, said arms being arranged and fitted within the aperture, the outer surface of the body being normally in facial contact with the inner surface of the rigid member with the lining overlying the inner surface of the body to form a substantially smooth surface on the inner face of the wall.

35 4. A pocket book handle installation as claimed in claim 3, wherein said body has means provided thereon for engaging the inner surface of the rigid member to locate the body and member against relative movement.

40 5. A pocket book installation as claimed in claim 3, wherein the opening registers with the uppermost portion of the aperture and said end strap portion of the handle has a terminating portion clamped to the body by the arms and a 45 connecting portion arranged substantially at right angles thereto and extending outwardly through the opening.
